UNITED STATES PATENT OFFICE.

JOHN HILL, OF COLUMBUS, GEORGIA.

AUTOMATIC FIRE-EXTINGUISHER.

SPECIFICATION forming part of Letters Patent No. 372,977, dated November 8, 1887.

Application filed December 2, 1886. Serial No. 220,507. (No model.)

To all whom it may concern:

Be it known that I, JOHN HILL, a citizen of the United States, residing at Columbus, in the county of Muscogee and State of Georgia, have invented new and useful Improvements 5 in Automatic Fire-Extinguishers, of which the following is a specification.

My invention relates to that class of apparatus for extinguishing fires in which the water or other fluid is conducted in suitable pipes under pressure to the point or points where its use may be required, and is there automatically liberated upon the occurrence of a conflagration, the fluid being liberated by the fusion of 15 a joint which confines the check-valve and distributor.

It is the purpose of my invention to provide a distributor to be used in automatic extinguishers of the kind shown in Letters Patent 20 No. 283,242, granted me August 14, 1883; No. 329,741, dated November 3, 1885, and No. 329,311, dated October 27, 1885, the parts having a novel construction, whereby the escaping stream of fluid is broken up and scattered over 25 all parts of the surrounding space, both above, below, and around the distributor-head.

The invention consists in the several novel features of construction and combinations of parts, hereinafter fully set forth, and definitely 30 pointed out in the claims annexed to this specification.

In the accompanying drawings, Figure 1 is a central vertical section showing my invention, the distributor being illustrated by whole lines in its working position and by dotted lines in the position it occupies when the solder joint is closed. Fig. 2 is a similar section illustrating the action of the parts. Fig. 3 is a transverse section of Fig. 1 in the line *x x*. 40 Fig. 4 is a central vertical section of Fig. 3 in the line *y y*. Fig. 5 is a side elevation of the parts shown in Figs. 3 and 4.

In the drawings, the reference-numeral 1 denotes the distributor-head of the usual form, 45 having an outlet or port, 2, provided with a valve-seat, 3, below which is a deflector-chamber, 4. Upon opposite sides of this chamber project arms 1^a, which support a seat, 5, having an orifice, 6, concentric with the chamber 4 and closed at its lower end by a seat, 7. These parts are not essentially different from 50 those shown in my patents already referred to.

The port 2 is closed by a valve, 8, having substantially the construction shown in Letters Patent granted me November 3, 1885, 55 No. 329,741. This valve is mounted on a vertical stem, 9, the lower end of which is supported by a sectional plate, 10, united by a soft-solder joint, and having a spring, 11, lying beneath it, by which, upon the fusion of the 60 solder, the parts of the plate are thrown off the seat.

Upon the stem 9 is mounted a distributor, 12, constructed as follows: The central portion, 13, is cup-shaped, or of the shape of the frustum of an inverted cone. This central space is surrounded by a ridge or annulus, 14, and partly surrounding the base of the outer sloping wall of this ridge is a flange, 15, which rises from the edge of the distributor and increases in height gradually until it meets a cross-ridge, 16, which lies between the annular ridge 14 and the end of the flange 15, and has one face, 16^a, sloping at an angle of about forty-five degrees, and an opposite face, 16^b, which 75 is nearly vertical. Upon the opposite side of the distributor is a similar cross-ridge having an oppositely-inclined face and a corresponding vertical face. These cross-ridges close the groove or channel 17 between the flange 15 and 80 the ridge 14.

It will be seen that at the point where the flange 15 joins the cross-ridge it is of equal height with said ridge and nearly as high as the annular ridge 14. From this point it decreases in height as it sweeps around the distributor until, at a point distant about thirty degrees of arc from the sloping face of the cross-ridge, it wholly disappears, leaving the outer face of the annular ridge plane, as shown 90 at 18. One of the flanges 15 is continued until it meets the sloping face of the cross-ridge, as shown in Fig. 3, and it follows that the inclination or pitch of this flange will be less than that of the other, and no plane surface is 95 left upon the outer face of ridge 14.

The action of the device is as follows: The fluid escaping from the port under pressure is formed by the deflector on the stem 9 into an annular stream, which is dependent for its 100 form and position upon the position of deflector in the chamber 4. The size of the disk and the position and diameter of the annular ridge 14 are such that the escaping

fluid strikes vertically upon the inclined inner and outer sides, instead of directly upon the plane central portion of the distributor inside the ridge 14. It flows outwardly over cross-ridges 16 and flanges 15, or inward over the plane surface of the central portion, 13, and up over the ridge on the other side. Each atom of water is directed according to the angle of the surface upon which it strikes, the law being that angles of incidence and reflection are equal. This law is modified in this case by the continually downpouring water, which breaks up and modifies the reflections. The fluid, striking at or near the outer base of the 15 annular ridge 14, will be reflected against the flange 15, where the latter is present, and the height of said flange will determine the angle of the second reflection caused by said flange. Where said flange is highest, the fluid will be directed upward and between that point and its lowest point at various angles outward and downward.

The action of the fluid will produce a vibration or oscillation of the stem 9 and distributor 25 12, caused by the flow of fluid to one side of the deflector. Some portions of the fluid will fall upon the inclined faces 16^a of the cross-ridges 16, and cause the distributor and stem on which it is mounted to rotate, so that both 30 a revolving and oscillating movement is obtained by which the angles of incidence are constantly changed and multiplied, making the distribution more uniform. Somewhat similar results can be produced by means of serrations of various forms; but the latter break up 35 and spray the water, whereby there is a tendency to destroy the directive power of the angles of reflection, and a considerably greater

pressure is required to effect a proper distribution through the serrations. In the form I have now invented the flow is more in streams, sheets, and heavy drops, and much less power or pressure is required to give a wide and equal distribution.

Having thus described my invention, what I claim is—

1. In an automatic fire-extinguisher having a chambered outlet, a distributor mounted upon a stem, said distributor having an annular ridge surrounding a central flat space, and two edge flanges of unequal length and pitch or obliquity, each flange sweeping around the edge of the distributor to a cross-ridge having one inclined and one vertical face, substantially as described.
2. In an automatic fire-extinguisher, a distributor having a plane central surface, an annular ridge surrounding said surface, and flanges extending partly around the distributor and of unequal length and pitch, substantially as described.
3. The combination, with the distributor-head having a port of the stem 9, having a valve closing said port, a distributor carried by said stem, and having circumferential flanges 15 of unequal length and pitch, a ridge, 14, and cross-ridges 16, each having an inclined face, 16^a, a soft-solder joint for supporting the valve, and a seat for the lower end of the valve-stem, substantially as described.

In testimony whereof I affix my signature in presence of two witnesses.

JOHN HILL.
